UNITED STATES PATENT OFFICE

159,441

COMBINED BIRDBATH AND SUNDIAL OR
SIMILAR ARTICLE

Vincent A. R. Primavera, Norton, Conn.

Application March 15, 1949, Serial No. 1,405

Term of patent 14 years

(Cl. D35—3)

To all whom it may concern:

Be it known that I, Vincent A. R. Primavera, a citizen of the United States, residing at Norton, in the county of Fairfield and State of Connecticut, have invented a new, original, and ornamental Design for a Combined Bird Bath and Sun Dial or Similar Article, of which the following is a specification, reference being had to the accompanying drawing, forming part thereof.

In the drawing the figure is a perspective view of a combined bird bath and sun dial or similar article, showing my new design.

I claim:

The ornamental design for a combined bird bath and sun dial or similar article, substantially as shown.

VINCENT A. R. PRIMAVERA.
